UNITED STATES PATENT OFFICE.

ORVILLE H. BOLEN, OF DENVER, COLORADO.

BUILDING-BLOCK.

SPECIFICATION forming part of Letters Patent No. 749,020, dated January 5, 1904.

Application filed May 22, 1903. Serial No. 158,369. (No model.)

To all whom it may concern:

Be it known that I, ORVILLE H. BOLEN, a citizen of the United States, residing at Denver, in the county of Denver and State of Colorado, have invented certain new and useful Improvements in Building-Blocks; and I do hereby declare the following to be a full, clear, and exact description of the invention, such as will enable others skilled in the art to which it appertains to make and use the same.

This invention relates to improvements in building-blocks, and particularly to such as are provided with effectual bonding means; and the object in view is the provision of a block which is designed to interlock with a similar block in such manner as to leave bonding-space therebetween for receiving cement or other sealing material.

With this and further objects in view the invention consists of a building-block formed with cyma surfaces the curves of which are designed to lie in planes out of parallel with the corresponding curves of interlocking blocks for providing curved bonding-material-receiving spaces therebetween.

It further consists of certain other novel constructions, combinations, and arrangements of parts, as will be hereinafter more fully described and claimed.

In the accompanying drawings, Figure 1 represents a perspective view of a building-block embodying the features of the present invention. Fig. 2 represents a view in side elevation of the same. Fig. 3 represents a fragmentary perspective view portion of wall made up of building-blocks similar to that disclosed in Figs. 1 and 2.

In the present art it is quite common to form building-blocks with corresponding parallel contiguous faces, whereby in positioning the blocks for producing a wall the cement employed has no spaces in which to lie for causing the blocks to cling together, and in order to effectually bond the blocks of a wall I employ bricks or blocks of the peculiar configuration illustrated in the accompanying drawings, in which 1 refers to a body portion of a block having a flat straight longitudinal edge 2 and flat straight ends 3. The upper and lower faces of block 1 are flat, but the edge opposite 2 is cutaway and formed with curved

lines, being first concaved, as at 4, and convexed, as at 5, arriving at a straight flat portion 6, extending across the central portion of the block parallel to the edge 2, the curve 4 commencing at a point spaced from the respective end 3 a distance equal to one-half the length of the flat portion 6, leaving a straight flat section 7 at each end of block 1. The concaved portion 4 is a greater curve than the curve of the convexed portion 5, whereby when the blocks are assembled, as indicated in Fig. 3, a space will be left between the curved edges thereof.

In assembling the blocks 1 in the form of a wall the same are arranged as illustrated in Fig. 3, with the parts 7 of one block lying in contact with the flat portions 6 of an oppositely-arranged block, the flat portion 7 of the next longitudinally-arranged block to the first-mentioned block also contacting with the flat portion 6 of the second-mentioned block, so that a perfect interlocking of the blocks is produced throughout the entire length of the wall. However, the cyma surface upon each end of each block produced by the concaved portion 4 and the convexed portion 5 have a contour not designed to fit snugly with the corresponding face of the contiguous block when the various blocks are assembled, but falling short of such contact by a distance sufficient for leaving a space having a compound curve, as at 8, for the reception of bonding material.

Having thus fully described my invention, what I claim as new, and desire to secure by Letters Patent, is—

1. A building-block comprising a body portion having one edge formed with outwardly-flaring cyma surfaces.

2. A building-block comprising a body portion having one edge formed with outwardly-flaring cyma surfaces, the curves of each surface being of such degree relative to each other as to leave a space between the same and the corresponding registering curves of a contiguous similar block.

3. A building-block comprising a body portion having one edge cut away and formed centrally with a flat, straight portion and curved in each direction away from the flat portion toward the ends of the body portion

each curve extending to a point at a distance equal to substantially one-half the length of the central flat portion.

4. A building-block comprising a body portion having one of its edges formed with cyma surfaces flaring from points near the center toward the ends of the body portion, one of the curves of each surface being greater than the other.
5. A building-block comprising a body por-

tion having one of its edges formed with cyma surfaces flaring outwardly from points near the center thereof.

In testimony whereof I hereunto affix my signature in presence of two witnesses.

ORVILLE H. BOLEN.
